COAT AND VEST HANGER

Edward E. Palmer, Fitzwilliam, N. H.

Application August 12, 1936, Serial No. 95,638

2 Claims. (Cl. 223—91)

This invention appertains to new and useful improvements in garment hangers, and more particularly to a hanger adapted for supporting both a coat and a vest or other article of apparel simultaneously.

An important object of the invention is to provide a combination coat and vest hanger wherein the vest is supported by the hanger without having the coat engaged thereon.

Another important object of the invention is to provide a combination device of the character stated which is of simple construction and of low cost to manufacture.

These and various other important objects and advantages of the invention will become apparent to the reader of the following specification.

In the drawings:

Figure 1 represents a front elevational view of the hanger shown supporting a coat and vest.

Figure 2 is a front elevational view of the hanger shown supporting a vest without the coat thereon.

Figure 3 is a front enlarged elevational view of the hanger with the intermediate portions thereof in section.

Figure 4 is an end elevational view of the hanger.

Figure 5 is a perspective view of the elongated vest supporting spring member.

Referring to the drawings, wherein like numerals designate like parts, it can be seen that numeral 5 represents the elongated arcuate-shaped coat hanging member which is provided with a transverse opening 6 at the intermediate portion thereof for receiving the intermediate portion of the hanger hook member 7. This member 7 is preferably of heavy gauge wire or rod material having its lower end bent to provide a straight inclined portion 8 and an upwardly inclined portion 9 embedded as at 10 in the arcuate member 5. The upper end of the member 7 is provided with the hook 11.

Numerals 12 represents the vest supporting spring rod, one end of which is embedded and anchored if necessary in the arcuate member 5 as at 13, while its opposite end is curved slightly

downward as at 14. This rod 12 is substantially parallel to the straight portion 8 of the rod 7.

As shown in Figure 1, a coat 15 is supported on the arcuate member 5, while a vest 16 is supported in clamped position between the rod 12 and the straight portion 8 of the rod or wire member 7.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A hanger of the character described comprising an arcuate-shaped coat hanging member, a hook member provided with a depending shank disposed through the intermediate portion of the arcuate-shaped member to depend below the same, the lower end portion of the said shank being bent in diverging relation to the intermediate portion of the arcuate member, and a spring rod having one end embedded in the hanging member and extending in diverged direction from the lower portion of the arcuate-shaped member and having its free end portion tensionally disposed against the diverged portion of the shank to hold a piece of garment between itself and the diverged portion of the hook shank, said diverged portion and spring rod extending downwardly with respect to the hanging member.

2. A hanger of the character described comprising an arcuate-shaped coat hanging member, a hook member provided with a depending shank disposed through the intermediate portion of the arcuate-shaped member to depend below the same, the lower end portion of the said shank being bent in diverging relation to the intermediate portion of the arcuate member, a spring rod extending in diverged relation from the lower portion of the arcuate-shaped member and adapted to hold a piece of garment between itself and the diverged portion of the hook shank, said hook shank being bent upwardly at its lower end and embedded in the arcuate member.

EDWARD E. PALMER.
